UNITED STATES PATENT OFFICE.

CHARLES J. HODGE, OF Houghton, Michigan.

DESIGN FOR A FRAME FOR SUPPORTING ORE OR MINERAL WASHING JIG-SCREENS.

SPECIFICATION forming part of Design No. 29,934, dated January 3, 1899.

Application filed December 12, 1898. Serial No. 699,074. Term of patent 7 years.

To all whom it may concern:

Be it known that I, CHARLES J. HODGE, a citizen of the United States, residing at Houghton, in the county of Houghton and State of Michigan, have invented and produced a certain new and original Design or Useful Shape for a Frame for Supporting Ore or Mineral Washing Jig-Screens, of which the following, in connection with the accompanying drawings, is a full, clear, and exact specification.

In the said drawings, Figure 1 is a plan view of a frame of the character described embodying my design. Fig. 2 is a transverse sectional view taken on the line 2 2, Fig. 1; and Fig. 3 is a side view, partly in section, on the line 3 3, Fig. 1.

The leading features of my design consist of the marginal frame portion A, the longitudinal undulating webs B, and the cross- webs C.

The frame A is rectangular and oblong and provided throughout in its upper surface at short intervals with circular sockets a, formed around which on their inner sides are bosses a', and the frame A on its inner sides at all points excepting where the bosses a' are formed and where the extremities of the webs B C merge with the frame A is beveled or rounded, as shown at a''.

The webs B C are very narrow as compared with their depth and also narrow as compared with the width of the frame portions A and coterminous in depth therewith, so that their upper and lower edges will be flush with or lie in the same plane as the upper and lower edges, respectively, of the frame A. The webs B C are intermerged, and all of them are tapered from bottom to top and their upper edges are rounded. The webs D are arranged longitudinally of the frame in parallel undulating lines, and the webs C connect such undulating lines at intervals and break joints with each other. The webs C are also slightly curved. At one end of the frame, on one of the cross-bars C, is formed a perforated boss D.

Having thus described my invention, what I claim as new therein, and desire to secure by Letters Patent, is—

The design for a frame for supporting ore or mineral washing jig-screens substantially as herein shown and described.

CHAS. J. HODGE.
